HENRY BOSSHARDT, SR., OF WEST HOBOKEN, NEW JERSEY.

METHOD OF PERFORMING OPERATIONS INCIDENTAL TO MACHINE-EMBROIDERY.

1,030,159.

Specification of Letters Patent. Patented June 18, 1912.

Application filed July 26, 1911. Serial No. 640,610.

To all whom it may concern:

Be it known that I, HENRY BOSSHARDT, Sr., a citizen of the United States, and a resident of West Hoboken, in the county of Hudson and State of New Jersey, have invented a new and Improved Method of Performing Operations Incidental to Machine-Embroidery, of which the following is a full, clear, and exact description.

10 My invention relates in general to a method of performing operations incidental to machine embroidery, and particularly to a method of forming a combined color-filled and embroidered fabric where figures are stenciled on the fabric instead of forming said figures by means of a color covering or leaf stitch, and relates more particularly to a method of pantographically forming a duplication of the figures on a pattern blank 15 and in forming outlining stitches bounding said figures after the same are stenciled on the fabric.

In explanation of the present advance in the art, it is noted that in one of two 25 methods now commonly used to obtain tinted or colored areas in embroidered designs where the stenciling method is used, the outlines of the areas to be colored are cut away by hand after the fabric is embroidered and different colored materials 30 are sewed to the back of the embroidered fabric, to correspond with the filled in portions of the pattern. It is obvious that this method is slow and expensive, and unless 35 great care is taken in cutting out the designs, a very ragged and unfinished effect is produced. Further, the product is very apt to be uneven and offer a patched effect owing to the two or more thicknesses of material.

40 By the second method the fabric along the desired outline is painted in by hand with the preferred combination of colors after the figures have been embroidered in outline. It is readily seen that by this method, 45 it is almost impossible to paint up to the outlining stitches without either touching them or leaving a ragged painted edge.

Attempts have been made to first paint the 50 design on the blank fabric and afterward stitch in the outlines, but it was found impossible to make the edges of the painted areas coincide with the stitches outlining the figures comprising the design, especially where machine devices were utilized in 55 carrying out, as far as possible, certain steps of the process.

One of the objects of my invention is to overcome the above-indicated objections by forming a stencil pantographically on an embroidering machine, by the use of which 60 stencil a combined tinted and embroidered fabric may be formed in one piece, and in which the edges of the tinted areas must necessarily coincide with the embroidered 65 stitches bordering the said tinted areas.

I will describe the invention in connection with certain features of a known form of embroidering machine that I may utilize in carrying out certain steps of my improved method, but it is to be understood that the 70 description of this method in which reference is made to an embroidering machine, is but a disclosure of one means to perform the method, and that I may make use of any form of machine or may even construct a 75 new machine in order to perform mechanically certain steps of the process.

Reference is to be had to the accompanying drawings, forming a part of this specification, in which similar characters of reference 80 indicate corresponding parts in all the figures, and in which—

Figure 1 is a front elevation of part of a pantograph embroidering machine, details of the same being omitted for clearness, and 85 showing a punctured stencil card sewed to the blank fabric in the floating frame; Fig. 2 is a plan of the stencil showing from right to left, three successive steps in its preparation; Fig. 3 is a view similar to Fig. 1 showing 90 the cut-out stencil in place with the stenciled areas showing through the cut-out portions of the stencil; and Fig. 4 is a fragmentary view showing the finished embroidered and tinted fabric.

Briefly, the method consists in imposing 95 a stencil blank on a fabric, delineating on the fabric the outlines of figures copied from a pattern, the locating of the stencil blank on the fabric, the removing of the stencil 100 to cut out the design so delineated, the re-locating of the stencil at its original position on the fabric, the stenciling in of the cut-out design on the fabric, and the stitching 105 of the outlines of said stenciled design.

The pantograph embroidering machine 110 readily adapts itself to certain steps of my improved process, and in carrying out my invention in correspondence with the example herein disclosed, a brief description is given of the essential parts of a pantograph embroidering machine in which it is to be

understood that there is a supporting framework 5 carrying a floating frame 6, which frame is adapted to carry the blank fabric 7 which it is desired to stencil and embroider. As is common with devices of this character, the frame 6 is supported and moved in a horizontal or vertical direction in the same plane, by means of a pantograph 8, the pointer 9 of which is adapted 5 to be moved over the usual enlarged pattern 10, fixed upon a pattern board 11, the movement of which pointer will be communicated to the frame 6, to bring the designs in position with reference to the embroidery needle 12 of each of the multiple 10 designs to the portion of the design corresponding to the portion of the pattern opposite the pointer 9. In other words, there 15 is disclosed in the drawings the essential 20 features of the ordinary pantograph embroidery machine.

With the desired pattern positioned on the pattern board and the blank fabric stretched on the frame 6, my novel method consists 25 in sewing or otherwise temporarily affixing a stencil blank 13 to the blank fabric. Suppose that it is desired to reproduce the design shown on the pattern in which the reproduction of the centrally-disposed triangle 30 angle 14 is to be tinted or stenciled with some color or combination of colors differing from the color of the blank fabric 7, and, further, that it is desired to outline this 35 stenciled area by means of some form of stepped or outlining stitches 15, as in the finished piece shown in Fig. 4, the pointer 9 is moved step by step along the outline on the pattern and at each step the embroidery needle 12 is caused to punch the stencil 40 blank with spaced-apart apertures 17, as shown to the right of Fig. 2. This outline may be duplicated pantographically across the bed of the fabric depending upon the number of needles 12 used. When the 45 desired outline of the pattern has been punched, the pointer 9 is carried to some starting point or point of reference 18, which I will designate as an "origin". With the pantograph pointer covering the origin 18, said 50 pantograph will be brought into the position shown in dotted lines in Fig. 3, the needle 12 being brought into position to engage the stencil blank at a point 18' corresponding with the similarly located point on the pattern. 55

After punching the stencil blank the needles are left in this position while the punched stencil 13 is removed by cutting away the holding stitches 19. Leaving the 60 needles in this position in the fabric will afford a means for replacing the stencil after it has been cut away, back in its original place, but it is not an absolutely necessary feature of this method that the stencil be 65 replaced in its original location, this step

being merely for the purpose of duplicating the design on the stencil in the exact reproduction of the pattern and in their correct relative positions. The areas outlined by the apertures 17 in the stencil blank is then 70 cut away, preferably by placing the stencil blank in a punching machine, to further perforate the stencil between the apertures 17 with fine, closely disposed apertures 20, as shown in the center of Fig. 2. This will 75 readily permit the punched areas 21 to be pressed out by the thumb or severed by a knife. The cut-out portion will form a stencil having a line of openings 22. The completed stencil is replaced on the blank 80 fabric carried by the floating frame of the machine, locating the same in its original position by hanging the stencil on the needles 12, preferably by inserting the stencil so that the needles will be positioned in the 85 perforations 18'. If the location of the stencil on the fabric has not been set as hereinbefore indicated, the pointer is now placed at the origin 18 or some other definite point 90 on the pattern, and the needles moved through to locate the positions of the perforations 18' on the fabric and stencil.

By means of a suitable brush, the fabric is stenciled through the cut-away portions 22, stenciling to the edges 24. Removing 95 the stencil, there is left a tinted area 23, as shown in Figs. 3 and 4. The pointer is then removed from the origin 18 to the edge 16 of the figure on the pattern, and the stenciled area outlined by a stitch of any desired color, which stitch may be a step stitch 24 or any other desired outlining stitch common in machine embroidery work. It will be seen that the exact shape of the area tinted was taken from the pattern, transferred 100 to the stencil and from the stencil directed to the fabric, so that not only will the exact shape be transferred to the blank fabric, but its location with reference to the embroidery needles is definitely and accurately fixed. 105 Further, if desired, any other form of embroidery stitch may be used to complete a fanciful design, and, as shown in the disclosure, the stenciled areas may be surrounded by circles or leaf stitch ellipses 25 and 110 the points 18' may be worked over by means of some fancy stitch 26 or buttonholed, as desired, but this last step is no part of the novel method. 115

Having thus described my invention, I 120 claim as new and desire to secure by Letters Patent:

1. In the production of designs on a fabric mounted on a pantograph embroidering machine, the method consisting of temporarily fastening a blank stencil card on the fabric; placing the pantograph pointer at an origin on the pattern carried by the embroidery machine; actuating the embroidering needles of the machine to mark corre- 130

sponding points on the stencil; actuating the pantograph pointer step by step to shift the stencil card relative to the needles; intermittently actuating the needles to puncture the stencil at the points thus presented to the needles; removing the stencil card from the machine and removing the punched areas from the card; re-locating the fabric relative to the needles by positioning the pointer at the origin on the pattern; forcing the needles through the fabric; re-locating the stencil with its marked origin on the needles, and finally stenciling in the design represented by the removed portions.

15 2. In the production of color filled embroidered figures, the method consisting of pantographically actuating a stencil blank to cause embroidering needles to delineate in

said stencil, the outlines of figures to be produced on the fabric; removing from the 20 stencil blank the areas within the figures thus delineated; stenciling on the fabric the figures represented by said stencil, and stitching the embroidered outlines by causing the embroidering needles to again go 25 over the paths previously traversed thereby in pantographically delineating the figures in the stencil blank.

In testimony whereof I have signed my name to this specification in the presence of 30 two subscribing witnesses.

HENRY BOSSHARDT, SR.
